REFRIGERATOR CABINET OR SIMILAR ARTICLE

Edward W. Harrison, Jefferson County, Ky., assignor to General Electric Company, a corporation of New York

Filed July 22, 1963, Ser. No. 75,911

Term of patent 14 years

(Cl. D67—3)

The figure is a front perspective view of a refrigerator cabinet or similar article embodying my new design, portions of the cabinet being shaded to indicate contrast.

The side wall not shown is substantially the same as the side wall shown. The rear wall not shown is conventionally plain.

I claim:

The ornamental design for a refrigerator cabinet or similar article, substantially as shown and described.
